UNITED STATES PATENT OFFICE.

MAURICE LEBOW, OF BALTIMORE, MARYLAND, ASSIGNOR TO DORF & COMPANY, OF BALTIMORE, MARYLAND.

ADJUSTABLE CAP.

Application filed February 1, 1922. Serial No. 533,178.

To all whom it may concern:

Be it known that I, MAURICE LEBOW, a citizen of the United States, residing at Baltimore, in the State of Maryland, have 5 invented certain new and useful Improvements in Adjustable Caps, of which the following is a specification.

This invention relates to an adjustable cap and has for its object to provide a cap of 10 such class, in a manner as hereinafter set forth, with means to provide for the conveniently adjusting thereof to fit the head of the wearer without producing uncomfortable wrinkles or distorting the appearance 15 of the cap.

A further object of the invention is to provide an adjustable cap, in a manner as hereinafter set forth, embodying two overlapping elements constituting a head band 20 depending from and connected to the cap body, and one of said elements having means for adjustably connecting the terminal portions thereof together to provide for the fitting of the cap without the forming or 25 producing of obtrusive wrinkles thereby overcoming an uncomfortable feeling when the cap is worn.

The invention will be best understood from a consideration of the following detailed description taken in connection with the accompanying drawings forming part of this specification, with the understanding that the invention is not confined to any strict conformity with the showing of the drawings, but may be changed and modified so long as such changes and modifications produce no material departure from the salient features of the invention as expressed in the appended claims.

40 In the drawings:

Figure 1 is a perspective view from a somewhat depressed level of a cap embodying the invention, some portions of the cap being broken away.

45 Fig. 2 is a side elevation of the cap embodying the invention with the contracting strap or band loosened.

Fig. 3 is a side elevation of the cap as

seen from the opposite side thereof and with the contracting strap or band loosened. 50

Fig. 4 is a section on the line 4-4 of Fig. 1.

Fig. 5 is a detail section through the rear portion of the body of the cap, on the line 5-5 of Fig. 1. 55

Fig. 6 is a section on the line 6-6 of Fig. 1.

Referring to the drawings in detail, 1 denotes a cap body, formed of any suitable material, preferably a flexible fabric and 60 which has its lower portion contracted. Arranged within the cap body as well as depending from the contracted lower portion thereof, is a lining 2.

Secured in proximity to its upper edge, as 65 well as intermediate the ends thereof, against the outer face of the back and sides of the contracted lower portion of the cap body 1, is a band 5, which depends from the said lower contracted portion of the cap body 1, 70 and opposes the depending portion of the lining 2, at the back and sides thereof. The lining 2, is secured to the inner face of the band 5, intermediate the ends of the latter and in proximity to the lower edge thereof 75 by rows of stitching 7. The band 5, is stiffened by a reinforcement 6, and which is secured to the band by the rows of stitching 7.

The securing of the band 5, intermediate its ends to the cap body 1, and lining 2, 80 provides the band 5 with disconnected terminal portions, indicated in Figures 1 and 3, at 8 and 9, and in Figure 2, at 18 and 19. The rows of stitching 7, are continued to the free termini of the extensions 8 and 9. The 85 terminal portion 9, is tapered as indicated at 11. The terminal portion 8, is provided with a buckle 12, so that the disconnected terminal portions 8 and 9, of the band 5, can be overlapped and adjustably connected together by the extending of the tapered end 11, of the terminal portion 9, through the buckle 12, carried by the terminal portion 8.

Secured to the contracted lower portion of the cap body 1, at the front portion thereof, as well as depending therefrom, is a 90

strip 13 and which is also secured to the depending portion of the lining 2. The rows of stitching 15, are employed for securing the strip 13, to the body 1, and to the lining 2. The rows of stitching 15, are arranged intermediate the ends of the strip 13, and in proximity to the upper and lower edges thereof. The stitching near the upper edge of the strip 13, secures the latter to the body portion 1, and the stitching 15, near the lower edge of the strip 13, secures the latter to the lining 2. As the strip 13, is secured intermediate its ends to the body 1, and lining 2, the said strip is formed with disconnected terminal portions indicated at 16, and which are tapered.

Secured to the inner face of that portion of the band 5, which is connected to the cap body 1, and in proximity to the free terminal portions of said band 5, are loops 17, through which are adapted to extend the disconnected terminal portions 16, of the strap 13, and which are interposed between the band 5, and the lining 2, as well as projecting rearwardly from the loops 17, as clearly shown in Figure 4.

Secured to the outer face of that part of the strip 13, which is connected to the body portion 1, is a pair of loops 22 for the disconnected terminal portions 8 and 9 of the band 5, as illustrated in Figures 1 and 3.

Secured to the lower edge of the strip 13, is a forwardly projecting visor 3, which has a sweat band 4, secured to the rear end of its inner face and which extends into the cap.

The visor 3, has its upper face provided with the male section of the socket fastener as indicated at 23, and which is adapted to detachably engage the female section of the fastener carried by the forwardly projecting portion of the cap body, as indicated at 24.

The band 5 and strip 13, form what may be termed the head band of the cap, and the said band 5, is constructed of flexible material and with that part thereof secured to the body 1, non-extensible. The strip 13, is formed of flexible material but that portion thereof which is secured to the body 1, is non-extensible. The band 5, as well as the strip 13, may be constructed of the same material from which the cap body 1 is formed.

When the band 5, is adjusted to provide for the fitting of the cap to the head of the wearer, the free terminal portions of the strip 13, slide along the sides of the cap thereby making provision for the take-up and prevent the forming of obtrusive wrinkles.

60 The termini of the connected portion of the strip are spaced from the termini of the connected portion of the band. The connected portion referred to in connection with the strip is that part thereof which is se-

cured to the body 1, and the connected portion referred to with respect to the band is that part thereof secured to the body 1, and by this arrangement during adjustment to fit, the free terminals of the band and strip can shift over each other and which relieves the body of the cap from strain when taking up or adjusting, and further there is no liability of the splitting or tearing of the cap during the taking up or adjustment operation, and furthermore the cap may be adjusted as closely to the head of the wearer as is desired.

What is claimed is:—

1. A cap comprising a body having a contracted lower portion, a split band encircling and depending from said lower portion and secured intermediate its ends to the outer face of the back and to each of the sides of said lower portion thereby providing oppositely extending free end terminal portions positioned at the front of said lower portion, a strip depending from and arranged against the outer face of the front and a part of each side of said lower portion, said strip secured intermediate its ends for a portion of its length to the outer face of the front of said lower portion thereby providing said strip with rearwardly directed free end terminal portions, the free end terminal portions of said strip sliding directly against the inner face of the connected portion of said split band, the termini of the connected part of said strip being spaced from the termini of the connected part of said band, and means for adjustably connecting the free end terminal portions of the band together for varying the size of the cap and for inclosing the connected portion of said strip.

2. A cap comprising a body having a contracted lower portion, a split band encircling and depending from said lower portion and secured intermediate its ends to the outer face of the back and to each of the sides of said lower portion thereby providing oppositely extending free end terminal portions positioned at the front of said lower portion, a strip depending from and arranged against the outer face of the front and a part of each side of said lower portion, said strip secured intermediate its ends for a portion of its length to the outer face of the front of said lower portion thereby providing said strip with rearwardly directed free end terminal portions, the free end terminal portions of said strip sliding directly against the inner face of the connected portion of said split band, the termini of the connected part of said strip being spaced from the termini of the connected part of said band, means for adjustably connecting the free end terminal portions of the band together for varying the size of the

cap and for inclosing the connected portion of said strip, loops connected to the inner face near each end of the connected part of said band for retaining the free end terminals of the strip against the inner face of the band, and loops secured to the outer face near each end of the connected part of the

strip for maintaining the free end terminal portions of the band against the outer face of the strip.

10

In testimony whereof I affix my signature hereto.

MAURICE LEBOW.
